UNITED STATES PATENT OFFICE

2,461,788

SHOOTING GALLERY

Walter A. Tratsch, Chicago, Ill., assignor to
Clarence E. Threedy, Chicago, Ill., trustee

Application February 7, 1945, Serial No. 576,625

2 Claims. (Cl. 273—95)

1

This invention relates to shooting galleries and has for its principal object the provision of a shooting gallery in which there are a plurality of abutting separate booths so arranged with respect to each other as to prevent the player occupying one booth from directing the aiming device in a direction other than at the target, thus assuring safety to observers standing adjacent the booths.

In shooting galleries of the character to which this invention relates, it is the common practice to use a plurality of moving targets toward which a pneumatically operated gun is directed, to propel a shot at the target. In such shooting galleries the entire space of the gallery is usually open and unobstructed, thus enabling the player to direct the gun at various undesirable angles other than at the targets. In so doing there are and have resulted numerous cases of injury by accident to observers where the player has moved the gun to such position as to bring the same within the line of position of the observers. At other times, observers have been injured by ricocheting of the shot from the targets. It is therefore one of the objects of this invention to provide a shooting gallery in which each player occupies a separate and independent booth, thus protecting those to the rear of the player from injury in the manner hereinbefore set forth.

Another object of the invention is the provision of an electric circuit which controls the operation of the aiming device and which will permit the operation of the aiming device only when the operator is confined in the booth with the door thereof closed.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a shooting gallery embodying my invention;

Fig. 2 is a symbolical diagram of the electric circuit which controls the aiming device of the shooting gallery.

The drawings illustrate the preferred form of construction by which the several objects of my invention are accomplished. In this connection my improved shooting gallery includes a target area 10 which is disposed a substantial predetermined distance from a partition 11. This partition 11 defines a plurality of abutting separate booths 12 and has an upper solid wall 13. Each

5 of the booths 12 are closed by hinge-supported doors 14. The lower portion of these doors 14 comprises a solid panel 16, whereas the upper portion comprises a transparent panel 15, and it is preferably intended the height of the lower portion of the door should be of a dimension approximate equivalent to the distance to the hip of a player.

In each of these booths there is provided a front railing 17 from which extends a suitable shelf 18. These shelves 18 are provided with openings 19 through which is adapted to pass a compressed air supply conduit 20 leading to the pneumatically operated gun or aiming device 21. 15 In the preferred showing of my invention, each of the guns 21 are supported upon their related shelf 18, with the barrel disposed upon the railing 17 within a notch 22.

Each booth has arranged therein an electric 20 circuit 24. In this electric circuit there is a coin controlled vending device 25 which may be of any approved construction capable of vending shots for use in the gun and which includes a suitable switch (not shown) adapted to be closed when 25 the coin slide 26 is in its full stroke position, that is a position to effect vending of the shots. This coin slide may be of any approved construction such as that shown in Patent No. 1,908,380. The compressed air supply conduit 20 has interposed 30 therein a valve 27, and this valve 27 is normally opened by a holding relay 28 also connected in the circuit 24, in which circuit there is a source of electric energy 29. A control switch 30 is disposed in the circuit 24, and this switch 30 is actuated by a magnetic coil 31 disposed in that part 24' 35 of the circuit 24. In this circuit 24' there is a master switch 32 which is normally closed when the door 14 of the booth is in closed position. In this circuit 24' there is also arranged a suitable 40 incandescent lamp 33 which substantially illuminates the booth.

To complete the invention there is suspended in any suitable manner forwardly of the transparent panel portion 15 of the doors 14, a suitable shade 34 which the player may lower so as to black out light or other interferences from that part of the shooting gallery to the rear of the booths as indicated at 35.

The gun or aiming device 21 is preferably constructed in accordance with the disclosure of Patent No. 2,304,320, granted December 8, 1942.

The arrangement is such that in order for the operator to manipulate the gun or aiming device 21, it is first necessary that he enter the 55 booth 12 and then close the door. Closing of

this door 14 closes the switch 32 which connects the circuit 24' with the source of electric energy 29. When this takes place the relay 31 will be energized and close the control switch 30, whereupon circuit 24 will be energized as and when the operator deposits a coin in the coin slide 26 and presses the slide inwardly to complete the circuit to the relay 28, which opens the valve 27 of the compressed air supply conduit 20, whereupon the pneumatic gun or aiming device is ready for operation by the operator. It will be thus seen that the operator occupying the booth cannot maneuver the gun to the rear of the booths so as to bring the same over the region occupied by observers. While prevented from thus doing, the side of the booth opposite the doors is open so as to permit him to have complete range of the targets 10.

While I have illustrated and described the preferred form of construction for carrying my invention into effect, this is capable of variation and modification without departing from the spirit of the invention. I, therefore do not wish to be limited to the precise details of construction set forth, but desire to avail myself of such variations and modifications as come within the scope of the appended claims.

Having thus described my invention, what I claim as new and desire to protect by Letters Patent is:

1. A shooting gallery comprising a booth having an open side and a door in the wall opposite said open side, an electric circuit having a source

of electric energy, a switch in said circuit normally closed when the door of the booth is closed, an aiming device in each of said booths comprising an electrically controlled member, and a coin-controlled device in each of said booths for connecting the electrically controlled member with said source of electric energy when said switch is closed by said door.

2. A shooting gallery comprising a booth having an open side and a door in the wall opposite said open side, an electric circuit having a source of electric energy, a switch in said circuit normally closed when the door of the booth is closed, a pneumatically operated gun in each of said booths comprising a compressed air supply conduit, a control valve for said conduit, and a relay in said circuit for opening said control valve, and a coin-controlled device in each of said booths for connecting the relay with the source of electric energy when said switch is closed by said door.
